[57] CLAIM

The ornamental design for a tree-mountable support, as shown and described.

DESCRIPTION

FIG. 1 is a top plan view of a tree-mountable support, showing my new design;

FIG. 2 is a left side elevational view thereof, the right side elevational view being a mirror image of FIG. 2; FIG. 3 is an end elevational view of the non-threaded end thereof; and,

FIG. 4 is perspective view thereof.

The bottom of the tree-mountable support is plain and unadorned.
